E. R. BURTNELL

INTERNAL COMBUSTION ENGINE

Filed April 9, 1925

UNITED STATES PATENT OFFICE.

EVERETT R. BURTNETT, OF LOS ANGELES, CALIFORNIA, ASSIGNOR, BY DIRECT AND MESNE ASSIGNMENTS, TO THE AUTOMOTIVE VALVES CO., OF LOS ANGELES, CALIFORNIA, A VOLUNTARY TRUST.

INTERNAL-COMBUSTION ENGINE.

Application filed April 9, 1925. Serial No. 21,826.

My invention relates generally to internal combustion engines, and more particularly to improvements in charge volume transfer manifolds for engines that operate by the 5 fresh charge being first inducted into a pump chamber and then transferred into a combustion chamber, the design as shown in the drawing forming a part hereof, being especially adapted for two stroke cycle internal combustion engines having three 10 units, and each unit having a pump chamber formed in the larger diameter of one cylinder of each unit of two cylinders.

The structure herein disclosed is an improvement on the transfer manifolds that 15 form the subject matter of my co-pending patent applications, Ser. No. 2527, filed Jan. 15th, 1925 and Ser. No. 20,117 filed April 2, 1925.

20 In both of the aforesaid applications, the transfer ducts were located externally of the cylinder block and all on the same side thereof.

Obviously, this arrangement increased to 25 a certain extent, the overall width of the engine and it is the principal object of my present invention to form the three ducts within the cylinder block between the outer side walls of said block, and the walls of the 30 cylinders therein and to locate the longer one of the ducts on one side of the cylinder block, and the other two shorter ducts on the opposite side of said block.

As a result of this arrangement, the width 35 of the cylinder block is minimized and the lengths of the respective of the respective ducts are shorter than if the ducts were externally arranged, consequently the distance of travel of the charge volumes from the 40 pumping or induction cylinders to the combustion cylinders is reduced to a minimum.

With the foregoing and other objects in view, my invention consists of certain novel features of construction and arrangement 45 of parts that will be hereinafter more fully described and claimed and illustrated in the accompanying drawings in which:

Fig. 1 is a horizontal section through the central portion of an engine cylinder block 50 that is provided with the internally arranged transfer ducts as contemplated by my invention.

Fig. 2 is a side elevational view of a cylin-

der block with parts in section and showing my improved arrangement of ducts.

55

Fig. 3 is an enlarged detail section taken on the line 3—3 of Fig. 1.

60

Referring by numerals to the accompanying drawings, 10 designates a cylinder block having six combustion chambers 11, 12, 13, 14, 15 and 16, the axes thereof being parallel and in the same plane.

65

The diameters of chambers 11, 13 and 15 are uniform throughout their lengths while the lower portions of chambers 12, 14 and 16 are increased in diameter to form charge volume pumping chambers 17, 18 and 19 respectively.

70

Pistons such as 20 having straight diameters are arranged for operation within combustion chambers 11, 13 and 15 and the smaller portions of two diameter pistons, such as 21 are arranged for operation within chambers 12, 14 and 16.

75

The larger portion 22 at the lower ends of piston 21, operate within the charge volume pumping chambers 17, 18 and 19.

A crank shaft 23 is mounted for rotary movement in four main bearings 24 in a crank case 25 and said crank is provided with three crank throws 26, 27 and 28 that are disposed 120° apart.

80

The pistons in chamber 11 and the two diameter chamber 12, 17 are connected to crank 26 by connecting rods 29, the pistons in chamber 13 and the two diameter chamber 14, 18, are connected to crank 27 by connecting rods 30 and the pistons in chamber 15 and the two diameter chamber 16, 19, are connected to crank 28 by connecting rods 31.

85

A head block 32 is secured on the head end of block 10 and formed in the underside of said block is a common compression and combustion clearance chamber 33 that connects the head-or-inner ends of chambers 11 and 12.

90

A second common compression and combustion clearance chamber 34 connects connects the inner ends of chambers 13 and 14 and a third clearance chamber 35 connects the head or inner ends of chambers 15 and 16.

95

Formed in the space between the outer wall of the cylinder blocks and the adjacent walls of the cylinders on one side of said block, and which space is ordinarily used as

100

105

a cooling fluid circulation cell or cells, is a charge volume transfer duct 36, that leads from the upper end of pumping chamber 19, to a transfer inlet port 37 that communicates directly with an annular chamber 38 and which latter has communication with the lower portion of combustion chamber 12 by means of ports 39.

Formed in the corresponding space on the opposite side of the block 10 and leading from the upper portion of pumping chamber 17 to chamber 40, that communicates with the lower portion of combustion chamber 14 by means of ports 41, is a charge volume transfer port 42.

The cross sectional dimensions of ducts 42 and 36 are equal so that the volume flow capacity through the two ducts is the same, but as the length of duct 42 is considerably shorter than duct 36, and it is necessary to obtain the same vacuum and precompression pressures in the pumping chambers, the volumetric displacement of duct 42 is increased and made equal to duct 36 by forming, immediately above duct 42 an auxiliary duct 43 and the latter having communication with duct 42 by means of an opening 44 that is formed through the lower end of the partition between said ducts.

Formed in the block 10 on the same side with duct 42 is a transfer duct 45 that is identical in size, form and construction with said duct 42 and said duct 45 from the upper end of pumping chamber 18 to an annular chamber 46, that surrounds the lower portion of combustion chamber 16 and has communication therewith through ports 47.

Duct 45 is provided on its top with an auxiliary duct 48 and thus ducts 42 and 45 are equal to each other and to longer duct 36 in both cross sectional dimensions and volumetric displacement so that the volume flow through all three ducts will be the same and the same vacuum and precompression pressures will prevail in all three pumping chambers.

As a result of my improved arrangement of ducts, charge volumes are pumped from pumping chamber 19 into combustion chamber 12 from pumping chamber 17 to combustion chamber 14 and from pumping chamber 18 to combustion chamber 16.

A particularly desirable feature of my invention is, the location of the transfer ducts in the spaces between the outer side walls of the cylinder block and the adjacent walls of the cylinders with the longer duct on one side and the two shorter ducts on the other side. Such arrangement enables the ducts to be formed in the engine block casting and does not increase the overall width thereof.

By forming the apertures 44 at the lower ends of the partitions between the main and auxiliary chambers of the shorter transfer

ducts, any condensation or liquid portions of the fuel mixture that might otherwise accumulate within the auxiliary chambers will drain through and fall in the rapidly moving charge volume that is passing through the duct at high velocity and thus be carried along and again mixed with said charge volume.

It will be readily understood that minor changes in the size, form and construction of the various parts of my improved internal combustion engine may be made and substituted for those herein shown and described without departing from the spirit of the invention, the scope of which is set forth in the appended claims.

I claim as my invention:

1. The combination with an internal combustion engine having six cylinders arranged in a row, three of which cylinders are provided with charge volume pumping chambers and with combustion chambers, of three charge volume transfer ducts arranged between the pumping chambers of said three cylinders and the combustion chambers within the other cylinders of said three cylinders, one of which ducts has greater length than the other two ducts, each shorter duct being provided on its upper portion with an auxiliary duct that has communication with the main chamber of the duct by means of an aperture located at the lower end of said auxiliary duct, and all three ducts being disposed inside the outer walls of the cylinder block.

2. The combination with an internal combustion engine having six cylinders, three of which are provided with charge volume pumping chambers and with combustion chambers, of three charge volume transfer ducts arranged between the pumping chambers of said three cylinders and the combustion chambers within the other cylinders of said three cylinders, one of which transfer ducts has greater length than the other two ducts, all of which ducts have the same volumetric capacity, and all three ducts being disposed inside the outer walls of the cylinder block.

3. The combination with an internal combustion engine having six cylinders, three of which are provided with charge volume pumping chambers and with combustion chambers, of three charge volume transfer ducts arranged between the pumping chambers of said three cylinders, and the combustion chambers within the other cylinders of said three cylinders, two of said transfer ducts being shorter than the third duct, a partition arranged within each shorter duct and dividing the space therein into a main chamber and an auxiliary chamber, and all three ducts being disposed inside the outer walls of the cylinder block.

4. The combination with an internal com-

- bustion engine having six cylinders, three of which are provided with combustion chambers and with charge volume pumping chambers, of three charge volume transfer ducts 5 arranged between the pumping chambers of said three cylinders and the combustion chambers within the other cylinders of said three cylinders, two of said transfer ducts being shorter than the third duct, a partition 10 arranged within each shorter duct and dividing the space therein into a main chamber and an auxiliary chamber, there being an opening formed through the lower portion of said partition for establishing communication 15 between the main and auxiliary chambers therein and said three ducts being disposed inside the outer walls of the cylinder block.
5. A charge volume transfer duct structure for six cylinders two stroke cycle internal combustion engines comprising three separate ducts, one of which is longer than the other two each shorter duct having connected main and auxiliary chambers where- 20 by the volumetric capacities of the chambers of the two shorter ducts are equal, and to the chamber within the longer duct, and all three ducts being disposed inside the outer walls of the cylinder block.
- 30 6. A charge volume transfer duct structure for six cylinder two stroke cycle internal combustion engines comprising three separate ducts, one of which is longer than the other, a partition within each shorter 35 duct for dividing the space therein into a main chamber, said partition being provided at its lower end with an opening that estab-
- lishes communication between said main and auxiliary chambers, and all three ducts being disposed inside the outer walls of the cylinder block.
7. The combination with an internal combustion engine having six cylinders, three of which are provided with combustion chambers and with charge volume pumping chambers, three charge volume transfer ducts arranged between the pumping chambers of said three cylinders and the combustion chambers within the other cylinders of said three cylinders, one of said ducts being longer than the other two, the three ducts 40 having the same volumetric capacity, the longer duct being located on one side of the cylinder block and the two shorter ducts being located on the opposite side of the cylinder block.
8. The combination with an internal combustion engine having six cylinders, three of which are provided with combustion chambers and with charge volume pumping chambers, three charge volume transfer ducts arranged between the pumping chambers of said three cylinders and the combustion chambers within the other cylinders of said three cylinders, one of said ducts being longer than the other two, the longer duct 45 being located on one side of the cylinder block, the two shorter ducts being located on the opposite side of the cylinder block and all three ducts being disposed inside the cylinder block.

In testimony whereof I affix my signature.

EVERETT R. BURTNELL.
